[57] CLAIM

The ornamental design for a cocktail table, as shown.

DESCRIPTION

FIG. 1 is a top perspective view of a cocktail table showing my new design;

FIG. 2 is a bottom perspective view thereof from the side opposite that shown in FIG. 1;

FIG. 3 is an end elevational view thereof taken from the lower left of FIG. 1; and

FIG. 4 is an exploded cross-sectional view thereof.

FIG. 1

FIG. 2

FIG. 3

FIG. 4
